United States Patent Office

Des. 220,103
Patented Mar. 9, 1971

220,103

INFANT'S BATH

Robert A. Clowe, Penfield, N.Y. 14526

Filed July 24, 1969, Ser. No. 18,373

Term of patent 14 years

Int. Cl. D23—02

U.S. Cl. D23—52

Fig. 1

Fig. 2

Fig. 3

Fig. 4

FIG. 1 is a perspective view of an infant's bath showing my new design;

FIG. 2 is a front elevation thereof;

FIG. 3 is a rear elevation thereof;

FIG. 4 is a side elevation thereof showing the side opposite that shown in FIG. 1.

I claim:

The ornamental design for an infant's bath, as shown.
